United States Patent Office.

IMPROVEMENT IN BRIDGES.

FREDERICK H. SMITH, OF BALTIMORE, MARYLAND.

Letters Patent No. 60,434, dated December 11, 1866.

The Schedule referred to in these Letters Patent and making part of the same.

TO ALL WHOM IT MAY CONCERN:

Be it known that I, FREDERICK H. SMITH, of Baltimore, Baltimore county, and State of Maryland, have invented a new and useful improvement in Suspension Trusses for Bridges, Roofs, &c.; and I do hereby declare that the following is a full, clear, and exact description of the same, reference being had to the accompanying drawings, forming part of this specification, in which—

Figure 1 is an elevation of the suspension truss applied to a bridge.

Figure 2 is a ground plan of the same.

Figure 3 is a sectional view.

Similar letters of reference indicate corresponding parts in the several figures.

The nature of my invention consists of a certain arrangement of braces, bars, posts, and straining beams, the whole composing a suspension truss for supporting roofs, floors, or building bridges, whereby the same strength as in other suspension trusses is obtained by the use of less material, greater simplicity of construction, by reason of the employment of fewer braces or bars, and less liability to expansion and contraction from sudden changes of temperature arises, and consequently less danger of injury to the structure.

To enable others skilled in the art to make and use my invention, I will proceed to describe it with reference to the drawings.

a a are the abutments, piers, or other supports; *B B* are the straining beams; *C C¹ C² C³* are the posts; *D D¹ D² D³ D⁴ D⁵ D⁶* are the braces or bars.

The operation of the truss, as applied to a bridge is as follows: The post *C*, is supported from the ends of the straining beam, *B*, by the bars or braces, *D D*. The posts *C¹ C¹*, are supported from the foot of post, *C*, by the bars or braces, *D¹ D¹*, prolongations of *D D*, and from the ends of the straining beam, *B*, by the braces or bars, *D² D²*. The posts *C² C²*, are supported from the feet of posts, *C¹ C¹*, by the braces or bars, *D³ D³*, prolongations of *D D¹*, and from the ends of the straining beam, *B*, by the braces or bars, *D⁴ D⁴*. The posts *C³ C³* are supported from the feet of posts, *C² C²*, by the braces or bars, *D⁵ D⁵*, prolongations of *D D¹ D³*, and from the ends of the straining beam by the braces, *D⁶ D⁶*. The upper ends of the posts, *C C¹ C² C³*, are attached to the straining beam, *B*, by any suitable connections, thus keeping the latter in place. By concentrating all the counter strains in a line, which is a prolongation of the line of the braces or bars, *D D*, in lieu of carrying them from the foot of each post, through separate small braces or bars, to the ends of the straining beam, great advantages are secured, such as simplicity and consequent facility of construction, economy of material, and more security from injury to the structure from sudden changes of temperature, as the material is disposed in large masses.

Having thus fully described my invention, what I claim as new, and desire to secure by Letters Patent, is—

Constructing a suspension truss in such a manner, that all posts other than the center post *C*, shall be supported by bars or braces, one of which as *D²*, extends from the foot of the post *C¹*, to be supported to an end of the straining beam *B*, and the other bar or brace *D¹*, supporting said post *C¹*, being in a prolongation of the line of the bar or brace *D*, supporting the center post *C*, from the opposite end of the straining beam, substantially as described.

To the above specification of my improvement in suspension trusses for bridges, roofs, &c., signed this 26th day of April, 1866.

FREDERICK H. SMITH.
